UNITED STATES PATENT OFFICE.

THEODORE VARNEY, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC-CIRCUIT CONTROLLER.

1,215,437.

Specification of Letters Patent. Patented Feb. 13, 1917.

Application filed May 27, 1912. Serial No. 700,055.

To all whom it may concern:

Be it known that I, THEODORE VARNEY, a citizen of the United States, and a resident of Pittsburgh, in the county of Allegheny and State of Pennsylvania, have invented a new and useful Improvement in Electric-Circuit Controllers, of which the following is a specification.

My invention relates to controllers for electric circuits and it has special reference to such controllers as are adapted to govern polyphase alternating current motors.

One object of my invention is to provide a controller of the class above indicated that shall have a relatively simple and durable means for automatically returning the controller to its off position upon the failure of voltage in one or more of the phases of the alternating current source of energy from which the controlled motor is supplied.

A second object of my invention, is to provide a particularly simple and durable contact structure for controllers of the aforesaid class. Various novel features will be hereinafter pointed out.

Figure 1 of the accompanying drawings is an elevation of a controller constructed in accordance with my invention, the inclosing tank or casing being broken away to disclose the operating mechanism and the switch contacts.

Figs. 2 and 3 are detail views of the controller operating mechanism, and Fig. 4 is a diagrammatic view illustrating the circuit connections of a motor control system embodying the controller of the other figures.

Referring to Figs. 1, 2 and 3 of the drawings, the controller here shown comprises a stationary frame 1 which forms a part of an inclosing casing, a cover 2, a fluid-containing tank or box 3, which is removably secured to the frame, a plurality of sets of stationary and movable contact members 4, 5, 6 and 7 (hereinafter referred to as contacts), an operating mechanism and a release magnet 8.

The stationary contacts 4 and 5 are mounted in parallel rows on an insulating plate or slab 9, to which they are secured by bolts 10.

The plate or slab 9 is supported in a substantially horizontal plane by a pair of yokes or brackets 11, which are bolted to

lug 12 of the stationary frame 1 and extend downwardly into the fluid-containing tank 3.

The brackets 11 are mounted in substantially parallel planes and support a shaft 13 which is rotatively mounted in a horizontal plane near the center of the tank or box 3.

A pair of castings 14 are secured to the shaft 13 between, and adjacent to, the respective bearing brackets.

An insulating strip or block 15, which is substantially parallel to the shaft 13, is secured to the castings 14 by bolts 16.

A link 18, which constitutes a portion of the operating mechanism, is connected to a projection 17 of one of the castings 14.

A plurality of contact-bearing members 19 are mounted on the insulating block 15 between the castings 14, and have perforated extensions 20 to which the contacts 6 and 7 are respectively pivoted.

Each of the contacts 6 and 7 is preferably provided with a removable contact tip which co-operates with the corresponding portion of one of the stationary contacts 4 and 5.

Each of the movable contacts is further provided with a downwardly extending bifurcated projection 21, and a spring 22 is interposed between the projections of each pair of opposite movable contacts. Each of the springs 22 is supported by a telescoping guide 23 having forked ends which engage pins 24 in the bifurcated projections 21.

The contact-bearing members 19 and the contacts themselves, are provided with co-operating stop projections 25, which are held in engagement by the action of the springs 22 and limit the rotative movements of the contacts on their pivots.

The operating mechanism comprises an operating shaft 26 which is rotatively supported by the frame 1 and is substantially parallel to the shaft 13, an operating lever 100 27, which is secured to the shaft 26, a stationary rod 28 which is mounted in the frame 1 and is parallel to the shaft 26 and a centering spring 29, which is coiled about the shaft 26 between a pair of pawls 30 105 and 31.

A pawl 33 engages a notch 34 in a cam 35 which is pivotally supported on the sta-

tionary frame 1 and prevents the movement of the operating handle 27 in one direction out of the off position of the controller.

A bell crank lever 32 is secured to the shaft 26, and the link 18 is pivotally connected to one of its arms. Its opposite arm 36 constitutes a latching pawl and is provided with a notch 37 at its outer end which is adapted to engage one end of a bell crank lever 38. The bell crank lever 38 is pivoted on a stationary pin 39 and its opposite end is connected to a movable core member 40 of the release magnet 8.

In addition to the movable core member 40, the release magnet comprises a coil 41 and a stationary core member 42 through which a guide rod 43 of the movable member extends.

The movable core member 40 acts vertically and a releasing pin 44 is mounted directly above it in the cover 2. The pin 44 has an extension 45 that projects through a hole 46 in the cover 2 and is adapted to engage the upper end of the rod 43 when pressed downwardly in opposition to a spring 47.

The body of the pin 44 slides in a recess 48 in a boss 49 of the cover 2. The spring 47 surrounds the extension 45 and is interposed between the body 44 and the bottom of the recess 48.

A pair of relay switches 50 and 51 and coils 52 and 53 of an auto-transformer are supported within the frame 1 near the magnet 8.

The tank or box 3 is preferably filled with oil or some other suitable insulating liquid which tends to quench the electric arcs produced when the co-operating contact members are separated.

The circuit connections for the system and the arrangement of the control contacts are illustrated in Fig. 4, to which reference may now be had.

As here shown, the group or set 4, of stationary contact members comprises contacts *a*, *b*, *c*, and *d*, and the group 6 comprises co-operating contacts *e*, *f*, *g* and *l*. The group 5 comprises stationary contacts *i*, *j*, *h*, *l*, *m* and *n*, and the group 7 comprises co-operating movable contacts *o*, *p*, *q* and *r*.

The controller is adapted to govern the circuits of a three-phase electric motor 54 which is supplied with energy from a generator 55 or from some other suitable source.

The operation of the controller and the circuit connections for the system are as follows:

Assuming that the controller occupies its off position, as shown in Fig. 1, all of the movable contacts are separated from the co-operating stationary contacts and the pawl 33 so engages the notch 34 as to prevent movement of the lever 27 in a clockwise direction. If the lever is moved in a counter-

clockwise direction, the block 15 and the movable contacts are given a rotary movement about the shaft 13 as an axis and the movable contacts 7 are forced into engagement with the stationary contacts 5.

This is the starting position of the controller and the operator should hold the lever in this position until the motor has attained a material speed. If the lever is released, the contacts will return to the position shown in Fig. 1 and the pawl 33 will fall back into the notch 34. If, however, the attendant throws the lever speedily in a clockwise direction from the starting position, through the off position, to the running position, the pawl engages the surface of the cam 35 and passes the notch 34 before the cam has an opportunity to resume the position shown in Fig. 1.

When the motor-operating position is attained, the end of the bell crank lever 38 engages the notch 37 in the pawl 36 by reason of the completion of an electric circuit through the coil 41 of the release magnet 8. The controller is accordingly held in the motor-operating position as long as the coil 41 continues to be energized or until the pawl 36 is manually released.

In the motor-starting position of the controller, the transformer coil 52 is connected across a pair of line conductors 56 and 57, the contacts *m* and *n* being bridged by the contacts *r*. The transformer coil 53 is similarly connected across the line conductors 58 and 57, the contacts *i* and *j* being bridged by the contact *o*. An intermediate tap 59 of the transformer coil 52 is connected, through contacts *l* and *q*, to one terminal 60 of the motor 54. A tap 61 of the transformer coil 53 is similarly connected, through contacts *h* and *p*, to a motor terminal 62. A third terminal 63 of the motor is connected, through contacts *r* and *n*, to the line conductor 57.

Relatively low-voltage energy is accordingly impressed on the motor windings in the starting position of the controller.

When the controller occupies its motor-running position, the motor terminals 60 and 62 are respectively connected, through the coils of the relay switches 51 and 50, to the circuit conductors 56 and 58, and the motor terminal 63 is connected directly to the circuit conductor 57. As long as the switches 50 and 51 are closed, the coil of the magnet 8 is connected across the circuit conductors 57 and 58.

It is, therefore, evident that the magnet 8 is energized except when the current supplied to the motor windings exceeds a predetermined value sufficient to cause either one or both of the switches 50 and 51 to open.

In case of failure of voltage on the supply circuit, the coil 8 will be deenergized and

will permit the spring 29 to return the controller to its off position. In a similar manner, if excessive current traverses either phase of the motor winding, one of the 5 switches 50 and 51 will open, the coil 8 will be deenergized and the controller will be permitted to return to its off position.

While I have shown my invention as applied to a three-phase motor, it is, of course, 10 not limited in this respect and the circuit connections and the contact members may be readily arranged to govern a two-phase motor.

Variations in structural details may also 15 be effected within the spirit and scope of my invention.

I claim as my invention:

1. A controller for electric circuits comprising two sets of stationary contact terminals, an intermediate rock-shaft, a contact-supporting member rotatively mounted upon the rock-shaft, two independently pivoted sets of contact terminals carried by said supporting member, means for resiliently connecting oppositely disposed pairs of said terminals and means for producing such rotative movements of the contact-supporting member as to effect engagement of the one or the other of its sets of contact 30 terminals with the corresponding stationary contact terminals.

2. A controller for electric motors comprising two sets of stationary contacts, an intermediate rock shaft, a set of movable contacts rotatively supported by the rock shaft, a lever for producing such a rotative adjustment of the rock shaft as to bring the movable contacts into engagement with one set of stationary contacts for motor-starting 40 and into engagement with the other set of

contacts for motor running and means dependent upon the engagement of the contacts in the motor-running position for locking the lever to maintain said position.

3. A controller for electric circuits comprising two sets of stationary contacts, an intermediate rock shaft, a set of movable contact-bearing members rotatively supported by the rock shaft, contacts pivotally secured to the contact-bearing member at 50 opposite sides of the rock shaft, stops for limiting the rotative movement of the movable contacts on their pivots, and springs interposed between pairs of movable contacts and tending to force them against said 55 stops.

4. A controller for electric circuits comprising two sets of stationary contacts, an intermediate rock shaft, a set of movable contact-bearing members rotatively supported by the rock shaft, contacts pivotally secured to the movable contact-bearing members at opposite sides of the rock shaft, stops for limiting the rotative adjustment of the movable contacts on their pivots, springs 65 interposed between pairs of opposite movable contacts and tending to force them against said stops, and means for producing such rotative movement of the rock shaft as to bring the movable contacts into engagement with either the one or the other set of stationary contacts.

In testimony whereof, I have hereunto subscribed my name this 24th day of May, 1912.

THEODORE VARNEY.
